[57] CLAIM

The ornamental design for a combined shelter and flower stand, substantially as shown.

DESCRIPTION

FIG. 1 is a perspective view of a combined shelter and flower stand showing my new design;
FIG. 2 is a left side elevational view thereof;
FIG. 3 is a right side elevational view thereof;
FIG. 4 is a front elevational view thereof;
FIG. 5 is a top plan view thereof; and
FIG. 6 is a rear elevational view thereof.
